FLYER FOR SPINNING AND LIKE MACHINES

Application filed March 24, 1928. Serial No. 264,387.

This invention relates to improvements in flyers for thread spinning and thread twisting machines, and has for one of its objects to provide an improved flyer of simple, practical and economical construction by means of which there is secured such a uniform tension on the thread as will reduce to a minimum the breakage incident to spinning and twisting operations, thereby obtaining increased efficiency and production.

Another object is to mount a flyer arm in such manner that the same will be securely maintained in position on the flyer body and at the same time be easily and quickly removed therefrom for replacement purposes.

A further object is to so mount the flyer arm or arms upon the body that the same will be securely retained thereon in a position where accidental contact of the hands of an operator with the retaining means, while the flyer is in operation, will be avoided.

The above and other objects will appear more clearly from the following detailed description, when taken in connection with the accompanying drawing, which illustrates a preferred embodiment of the inventive idea.

In the drawing—

Figure 1 is an elevational view showing the improved flyer mounted upon a spindle in association with a bobbin thereon;

Figure 2 is a fragmentary vertical sectional view taken substantially on the line 2—2 of Figure 1;

Figure 3 is an enlarged fragmentary sectional view through the flyer;

Figure 4 is a bottom plan view of the flyer showing one of the flyer arms or wires in position thereon;

Figure 5 is a plan view of one of the arms or wires;

Figure 6 is a perspective view of the flyer showing two arms or wires carried thereby; and

Figure 7 is a bottom plan view of the construction shown in Figure 6.

Referring more particularly to the accompanying drawing, the numeral 10 indicates a spindle of a spinning or like machine having the usual tapered extension 11 upon

which is mounted the bobbin 12 containing the thread or threads to be twisted, the spindle 10 being rapidly rotated in the customary manner as by the engagement of a belt with the main portion of the spindle.

The flyer, which includes the essential features of the present invention, comprises a body preferably made of wood and consisting of a hub portion 13 with a disk-like portion 14 at one end of said hub portion and extending laterally therefrom. The body is provided with a central opening for receiving the extension 11 of the spindle after the bobbin 12 has been mounted thereon and said opening is sufficiently large to permit of a free rotation of the flyer about the spindle when in operation. The end of the hub portion 13 opposite the disk 14 is adapted to rest against the adjacent end of the bobbin 12 with the under surface of the disk 14 opposed to said end of the bobbin and in spaced relation thereto.

To reinforce the disk 14 and provide a means for supporting the flyer arm or arms on the body of the flyer, there is preferably provided a metal cap 15 having a central opening for receiving the hub portion 13 and engaging the under surface of said disk with the outer edge of the cap turned upwardly about the periphery of the disk 14 and terminating substantially flush with the upper surface of said disk.

The retaining means for supporting the flyer arm or arms upon the body of the flyer is preferably formed upon the under surface of the cap 15 so as to minimize the possibility of an operator's hands coming in contact with said means while the flyer is in operation. The retaining means comprises two pairs of lugs 16 struck from the cap 15 on diametrically opposite sides of the hub portion 13 with said lugs extending in opposite directions toward each other and the free ends thereof spaced to form an entrance opening 17 therebetween for the flyer arms. Also at oppositely disposed points the cap 15 is provided intermediate the pairs of lugs 16 with other single lugs 18 each of which extends in an opposite direction from the adjacent lugs of the pairs 16. With this con-

struction one or more flyer arms or wires 19 and 20 may be secured in position on the underside of the cap 15 by engagement with a series of lugs, with the free ends of the wires extending on opposite sides of the flyer body. The wires 19 and 20 differ in construction only in that the former has its extremities 21 bent so that when the wire is in position said extremities will extend downwardly, as shown in Figure 1, while the extremities of the wire 20 are in the same plane as the remaining portion of the wire. When two such wires are used, as shown in Figure 6, the loops of the respective wires, through which the threads are passed, will be in different horizontal planes and will have the effect of exerting a strong tension or pull upon the threads passing through said loops at an angle to the wires.

Each of the arms or wires is bent intermediate its ends to provide angular portions 22 which diverge from a common point 23. When mounting a wire upon the body of the flyer the point 23 is first engaged beneath one of the lugs 18 and then by a spring action the ends of the angular portions may be inserted through the opposed openings 17 between the lugs of each pair 16. Then, due to the resiliency of the wire, the portions thereof contiguous to the ends of the angular portions 22 will engage beneath the lugs 16 adjacent the lug 18 with which said wire is held. Thus the wire or arm is securely attached to the flyer body and may be readily detached therefrom by a reversal of the operation just described when it is desired to rewire the flyer.

In cases where two wires are employed as in Figures 6 and 7, the second wire is mounted in the same manner as above described, and said wires are then bent, as clearly shown in Figure 7, to diverge outwardly from the pairs of lugs 16 to separate laterally the loops at the extremities of the wires.

After mounting a flyer upon the extension 11 of the spindle above the bobbin 12, as shown in Figure 1, the milled nut or head 24 having a tapered opening therethrough is forced upon the upper extremity of the extension 11 so as to be tightly wedged thereon, said head forming an abutment which will prevent accidental detachment of the flyer from the spindle while in operation.

What is claimed is:

1. A flyer comprising a body adapted for rotation on a bobbin spindle and having an under surface, a cap secured to said under surface and having flyer arm-retaining lugs contiguous to said surface, and a flyer arm supported by said lugs.

2. A flyer comprising a body adapted for rotation on a bobbin spindle, flyer arm-retaining means carried by said body and including opposed lugs thereon extending in one direction, another lug intermediate said

opposed lugs and projecting in an opposite direction from that of the latter lugs, and a flyer arm having portions supported by said lugs to mount said arm in position on the body.

3. A flyer comprising a body adapted for rotation on a bobbin spindle, flyer arm-retaining means carried by said body and including opposed pairs of lugs, with the lugs of each pair extending in opposite directions to each other and having adjacent free ends forming an entrance opening, other lugs on said body in opposed relation to each other and disposed between said pairs of lugs, each of said other lugs extending in an opposite direction to that of the adjacent lugs of said pairs, and flyer arms each engaged with one of said other lugs and with the adjacent lugs of said pairs.

4. A flyer comprising a body adapted for rotation on a bobbin spindle and having an under surface, a cap secured to said under surface and having flyer arm-retaining means on said surface, said means including opposed lugs thereon extending in one direction, another lug intermediate said opposed lugs and projecting in an opposite direction from that of the latter lugs, and a flyer arm having portions insertable beneath said lugs to mount said arm in position on the body.

5. A flyer comprising a body adapted for rotation on a bobbin spindle and having an under surface, a cap secured to said under surface and having flyer arm-retaining means on said surface, said means including opposed pairs of lugs, with the lugs of each pair extending in opposite directions to each other and having adjacent free ends forming an entrance opening, other lugs on said body in opposed relation to each other and disposed between said pairs of lugs, each of said other lugs extending in an opposite direction to that of the adjacent lugs of said pairs, and flyer arms each engaged with one of said other lugs and with the adjacent lugs of said pairs.

6. A flyer comprising a body adapted for rotation on a bobbin spindle and including a hub portion and a disk-like portion carried thereby, a cap for said disk-like portion having an under surface, opposed lugs struck from the under surface of said cap and extending in the same direction therefrom, another lug also struck from said under surface at a point intermediate said opposed lugs and extending in an opposite direction from that of the latter lugs, and a flyer arm having angular portions intermediate its ends diverging from a common point, said arm being retained in position on said cap with said point engaged with said other lug and the ends of said angular portions held by said opposed lugs.

7. A flyer comprising a body adapted for rotation on a bobbin spindle and including a hub portion having one end engageable

with a bobbin on said spindle, a disk portion at the other end of said hub portion and of greater diameter than the latter, and means on the under surface of said disk portion for detachably securing a flyer arm to said body.

5 8. A flyer comprising a body capable of rotation upon a bobbin spindle and having an under surface, flyer arm-attaching means on said surface comprising a plurality of 10 lugs, certain of which extend in an opposite direction from the remainder thereof, and a flyer arm engaged with said lugs and supported in position thereby.

15 9. A flyer comprising an integral body having a hub portion and a disk-like portion at one end of said hub portion, said disk-like portion presenting an under surface, and a cap secured to said under surface and having flyer arm-retaining means thereon.

20 10. A flyer comprising a body having a disk-like portion and a reduced hub portion extending from the first-named portion and adapted for rotation on a bobbin spindle, and flyer arm-attaching means carried by said 25 disk-like portion on the under surface thereof.

In testimony whereof we have affixed our signatures.

PETER DAUGERT.
